US00D930091S

(12) **United States Design Patent** (10) **Patent No.:** **US D930,091 S**
Wang (45) **Date of Patent:** **** Sep. 7, 2021**

(54) **DUMBBELL**

(71) Applicant: **JINAN RUNWE HEALTH TECHNOLOGY CO., LTD**, Jinan (CN)

(72) Inventor: **Xingqiang Wang**, Jinan (CN)

(73) Assignee: **JINAN RUNWE HEALTH TECHNOLOGY CO., LTD**, Jinan (CN)

(**) Term: **15 Years**

(21) Appl. No.: **29/759,936**

(22) Filed: **Nov. 26, 2020**

(51) LOC (13) Cl. **21-02**

(52) U.S. Cl.

USPC **D21/681**

(58) **Field of Classification Search**

USPC D9/668, 600, 542, 538, 503; D8/331; D7/697, 625, 515, 507; D21/803, 694, D21/681, 680, 679, 678, 662; D11/81; 482/99, 8, 50, 111, 110, 108, 107, 106, 482/105, 104

Primary Examiner — Ryan Harvey

(57) **CLAIM**

The ornamental design for a dumbbell, as shown and described.

DESCRIPTION

FIG. 1 is a perspective view of a dumbbell showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the dumbbell where the dumbbell is in a configuration of use; and,

FIG. 10 is an enlarged view of portion 10 shown in FIG. 1. The broken lines in the drawings depict portions of the dumbbell that form no part of the claimed design.

1 Claim, 10 Drawing Sheets
